PULL-IN CLOTHESLINE

Reuel R. Robertson, Easton, Pa.

Application January 5, 1937, Serial No. 119,161

1 Claim. (Cl. 211—119.05)

This invention relates to pull-in clothes lines of the general type adapted to be attached to an upper story window, as for example, an apartment house window, and adapted to be extended through the open window into the room when hanging or removing a wash.

Ordinarily clothes lines of the slide type when pushed out of the window remain extended to full length horizontally outward from the building. Also the arms are necessarily limited in length to the height of the lower sash, for example, three feet or more so that they may be extended into the room through the raised lower sash. With these disadvantages of prior pull-in clothes lines in mind, the present invention provides a long jointed and sliding arm which may be extended into the room approximately ten feet if desired and which when pushed out of the window will not extend outward from the building but will automatically assume an upright position parallel with the wall of the building.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawings forming part of this specification,

Figure 1 is a side elevation of a pull-in clothes line constructed in accordance with the invention and shown projecting into the room.

Figure 2 is a side elevation of the clothes line shown in operative position parallel with the wall of the building.

Figure 3 is a front elevation of the clothes line in the operative position shown in Figure 2 looking toward the building.

Figure 4 is an enlarged detail cross sectional view taken on the line 4—4 of Figure 3.

Figure 5 is a cross sectional view taken on the line 5—5 of Figure 4.

Figure 6 is a perspective view of the guide for the slide arm.

Figure 7 is a detail sectional view showing the stop pin and notch in the slide arm receiving the pin to hold the slide arm stationary when the wash is being hung upon or removed from the clothes line.

Referring now to the drawings in which like characters of reference designate similar parts in the various views, 10 designates an upright bar having at the bottom a foot 11 which is adapted

to be secured by screws or otherwise to the sill 12 of a window outside of the window frame 13. The bar is disposed adjacent to the wall of the building so as to be out of the way.

A disc 14 is provided with a central opening 15, best shown in Figure 4, to receive a pin 16 which is screwed into the upright bar 10. The disc is anchored to an angle iron plate 17 by means of hinges 18 and a turnbuckle 19, the angle iron plate being bolted as shown at 20 or otherwise rigidly secured to the building wall. Adjustment of the turnbuckle when mounting the device provides for correct alignment of the clothes line with the clothes line supporting post 21, shown best in Figure 1.

The disc 14 forms a wear plate or support upon which the jointed extensible member of the device may rotate when the clothes line is being projected into or out of the room. The member comprises a slide arm 22 which is slidably fitted in a guide arm 23 to slide endwise thereon, the guide arm having a strap 24 at one end which loosely embraces the slide arm. The guide arm moreover is provided with an opening 25, best shown in Figure 6, which passes through the sides of a U-shaped extension 26 that receives the slide arm. The above mentioned pin 16 passes through the opening 25 as best shown in Figure 4 and anchors the guide arm to swing in an arc on the pin 16, to extend the clothes line 30 into the room or to dispose the clothes line outside of the room. A right angular stop pin 27 is disposed on the extension 26 and overlies the space between the legs of the extension to prevent the slide arm 22 from escaping from the guide arm 23. 35

The slide arm is equipped at one end with a pulley 28 over which the clothes line 29 is trained. At the opposite end the slide arm is pivotally connected to one end of a link 30, as shown at 31. The opposite end of the link is pivoted to the upper end of the upright bar 10 as shown at 32 in Figure 1. The pulley 28 is equipped with a pin 33 forming a grip. When the slide arm and the guide arm are rocked downwardly by means of the grip 33 from the position shown in Figure 1 to the position shown in Figure 2 the guide arm will rock on the pivot pin 16 and simultaneously therewith the link 30 will swing in an arc on its pivot 32 and slide the slide arm longitudinally of the guide arm to extend vertically and parallel with the wall 34 of the building as illustrated.

The clothes line 29 is trained over a pulley 35 carried by the post 21 and also is trained over a pulley 36 carried by a bracket 37 that is fixed to 55

one leg of the extension 26 of the guide arm as best shown in Figure 3.

The clothes line is then trained over a pulley 38 which is secured to a link 39 that is pivotally connected to a bracket 40 secured to the upper end of the slide arm, the pivot pin of the link being indicated by the numeral 41 as shown in Figures 1 and 2. The link 39 swings on its pivot 41 to a horizontal position when the clothes line is extended into the room as shown in Figure 1, and to a vertical position as shown in Figure 2 when the clothes line is disposed outside of the room.

A notch 42, best shown in Figures 2 and 7, is formed in one edge of the slide arm 22 and this notch receives the beforementioned pin 16, as shown in Figure 5, when the clothes line is extended into the room and prevents the slide arm from moving outwardly from its set position when a wash is being hung upon or removed from the clothes line.

The pin 16 is provided with a knob 43 which forms a stop to prevent escape of the clothes line when the lower reach of the clothes line is lifted vertically after the line has been filled with clothes and looped over the pin 16, as indicated in Figure 2, to tension the line when the device is disposed outside of the room.

In operation the device normally extends vertically from the sill 12 along side of the wall of the building and parallel thereto. To extend the clothes line into the room the knob 33 of the pulley 28 is grasped and the combined slide arm and guide arm are rocked upwardly. During this movement of the parts the link 30 will rock

and the slide arm and guide arm will assume a horizontal position while the pin 16 rides into the notch 42 in the slide arm 22 at the moment the arms assume horizontal position. The wash may now be hung upon the line and when this has been completed the lower reach of the line is grasped and hooked over the pin 16, as best shown in Figure 3. This tensions the line. Thereupon the knob 33 may again be grasped and rocked downward, the lower pivoted end of the link 30 simultaneously moving upward in an arc to lift the slide arm from engagement with the pin 16.

During continued downward swinging movement of the lower pulley in the direction of the arrowheads shown in Figure 1 the slide arm and guide arm will assume vertical position as indicated in Figures 2 and 3 outside of the building.

From the above description it is thought that the construction and operation of the invention will be fully understood without further explanation.

What is claimed is:

A pull-in clothes line comprising a guide arm, a slide arm movable endwise of the guide arm, means for pivotally attaching the guide arm at 25 one end to a stationary support, a link pivotally connecting one end of the slide arm to one end of the support for guiding said slide arm longitudinally of said guide arm when said guide arm is rocked on its pivot, a pulley on one end of the 30 guide arm, a pair of pulleys on the slide arm one of which is pivotally connected to the slide arm, and a loop clothes line having one loop thereof trained over said pulleys.

REUEL R. ROBERTSON.
